UNITED STATES PATENT OFFICE.

PER BERGGREN, OF BROOKLYN, NEW YORK.

DRAFTING-PEN.

1,117,475.

Specification of Letters Patent. Patented Nov. 17, 1914.

Application filed March 12, 1913. Serial No. 753,712.

To all whom it may concern:

Be it known that I, PER BERGGREN, a subject of the King of Sweden, residing at Brooklyn, in the county of Kings and State of New York, have invented certain new and useful Improvements in Drafting-Pens, of which the following is a specification.

The present invention has reference to drafting pens, and it proposes an improved implement of that general type or class which is designed primarily for use in making topographic drawings.

It comprehends the provision of improved means or devices for making the broken lines used in drawings of the character specified, and, further, of additional improved means which permit the blade of the pen to be turned or rotated for the purpose of drawing the wavy or sinuous lines indicative of mountain ranges and the like.

An embodiment of the invention is illustrated in the accompanying drawing, whereof:

Figure 1 is a part-sectional side elevation of the improved pen; Fig. 2 is an enlarged detail view, showing the mounting of the marking device; and Figs. 3 and 4 are, respectively, fragmental side and front elevations of a modification.

In said drawing, 5 indicates, generally, the handle portion of the pen, 6 the blade, or pen proper, and 7 the marking device. The part last mentioned is preferably constituted by a wheel whose peripheral edge is divided by a series of radial notches or gaps 8 which extend inwardly therefrom toward the center of the wheel and thus result in the production of separated or spaced teeth 9. Any number of these notches or gaps may be formed, as will be understood, and it will be further apparent that their width and general shape, as well as the distance between them, may be varied in accordance with the character of the lines to be drawn. The aforesaid wheel is revolvably mounted upon a pin 10 which is rigidly secured at one end to one of the arms of the pen blade, adjacent the tip or terminal thereof, and is removably fitted at its other end in a correspondingly-located opening 11 provided in the other arm, the wheel itself being loose upon this pin, in consequence whereof it may be withdrawn and replaced by a wheel of different size, or differently notched periphery. Provision

for this substitution of wheels is made through the agency of the usual adjusting screw, the shank 22 of which is engaged in perforations in the blade arms. When the nut 12 on said shank is rotated in the proper direction, the terminals of said arms are permitted to move away from each other, thereby disengaging the free end of the pin 10 from the opening 11. On rotating said nut in the other direction, the terminals of said arms are forced toward each other. This mounting holds true for all forms of the invention.

In order to draw parallel lines, as in indicating mountain ranges, the periphery of the wheel is also formed with a groove 13, which is intersected by the notches 8, and where fine lines are to be drawn, the ink is supplied directly to the groove in the ordinary manner, but where the character of the work is such as to require heavy lines, a feeder 14 may be utilized. This feeder conforms generally to the shape of the blade, and is preferably used in connection with pens of the conventional or straight-armed type, as shown in Figs. 3 and 4. In the form therein depicted, the feeder embodies a pair of arms which are connected together at their inner or upper ends and are disposed between the arms of the blade. These feeder arms are formed with alining openings through which the shank 22 of the adjusting screw passes. The portion which connects the aforesaid inner or upper ends of the feeder arms may itself be fastened by any desired means to the handle end, between the bases of the blade arms, or the feeder may be held in place solely by the adjusting screw. The extremities of the feeder arms project into the wheel groove, for supplying the ink thereinto.

With the blade, there may also be utilized a guide 15, here shown as in the form of an arm having a longitudinal slot 16 through which a threaded pin 17 projects. Said arm is disposed against one of the arms of the blade, as represented in Figs. 3 and 4, and may be held in adjusted position by means of a clamping head 18 and a washer 19 which are carried by pin 17, said pin being disposed transversely of the blade and suitably affixed thereto. The guide may be used either with or without the feeder 14, as will be understood, according to the character of the lines to be drawn.

Where the blade is to be used for drawing wavy or sinuous lines, it is mounted upon the handle in such a way as to permit it to be manually turned or swung laterally relatively to said handle by the operator, and the arms of said blade are given a somewhat angular shape, the lower or wheel-carrying portions thereof being offset or disposed at an angle to the upper portions, as depicted in Fig. 1. Provision is made for this rotary movement of the blade by rigidly connecting it at its base to a rod 20 that extends through the axial bore of the handle, the latter, in such instance, being made tubular. The upper end of this rod projects beyond the end of the handle, is threaded, and carries a cap nut 21 which, when turned in one direction, will become tightened against the upper end of the handle, and, in consequence, will hold the blade against rotation.

I claim as my invention:—

1. A drafting pen comprising a tubular handle, a blade having an axial extension revolvably fitted in the bore of said handle, and a member carried by said extension for holding the same against revolution.
2. A drafting pen having a blade comprising a pair of coöperating arms, and a marking wheel mounted between the extremities of said arms and having its periphery formed with a continuous groove and with radial notches intersecting the same for drawing broken parallel lines.
3. A drafting pen comprising a tubular handle, and a blade having its lower portion disposed at an angle to its upper portion, and its said upper portion provided with an

axial extension which is revolvably fitted in the bore of said handle.

4. A drafting pen comprising a tubular handle, a blade having its lower portion disposed at an angle to its upper portion, and its said upper portion provided with an axial extension which is revolvably fitted in the bore of said handle, and a member carried by said extension for holding the same against rotation.

5. A pen for drawing parallel sinuous lines comprising a tubular handle, a blade having its lower portion disposed at an angle to its upper portion, and its said upper portion provided with an axial extension which is revolvably fitted in the bore of said handle, and a peripherally notched marking wheel revolvably mounted at the extremity of said blade.

6. A pen for drawing broken parallel sinuous lines comprising a tubular handle, a blade having its lower portion disposed at an angle to its upper portion, and its said upper portion provided with an axial extension which is revolvably fitted in the bore of said handle, and a marking wheel revolvably mounted at the extremity of said blade, the periphery of said wheel being formed with a continuous groove and with radial notches intersecting the same.

In testimony whereof I have hereunto set my hand in presence of two subscribing witnesses.

PER BERGGREN.
